(57) CLAIM

The ornamental design for medical exam gown, as shown and described.

DESCRIPTION

FIG. 1 is a perspective front view of a medical exam gown; FIG. 2 is a front elevation view of the medical exam gown; FIG. 3 is a rear elevation view of the medical exam gown; FIG. 4 is a left side elevation view of the medical exam gown, the right side elevation view being a mirror image thereof; FIG. 5 is a top plan view of the medical exam gown; FIG. 6 is a bottom plan view of the medical exam gown; FIG. 7 is a perspective front view of the medical exam gown, shown in use on a patient; and, FIG. 8 is a perspective front view of the medical exam gown, shown in use on the patient. The patient is shown in broken lines to represent environment and form no part of the claim.
